UNITED STATES PATENT OFFICE.

WALTER S. SMITH, OF ELIZABETH, NEW JERSEY, ASSIGNOR TO WILLYS CORPORATION, OF NEW YORK, N. Y., A CORPORATION OF DELAWARE.

AUTOMOBILE DOOR AND METHOD OF SECURING PANELS THERETO.

Application filed December 28, 1920. Serial No. 433,675.

This invention relates to metal vehicle doors and the means and method for securing the leather, fabric, or other flexible covering or facing to the inner face thereof.

5 The object of the invention is to simplify and improve the construction of automobile doors and the method of assembling the panel therewith, and to provide a neat and durable construction which is economical 10 to manufacture.

The invention consists substantially in the construction, combination, location and relative arrangement of parts, and the method, all as will be more fully hereinafter set 15 forth, as shown in the accompanying drawing, and finally pointed out in the appended claim.

Fig. 1 is a view in perspective of a metal automobile door showing the panel secured 20 to the inner face thereof.

Fig. 2 is a fragmentary sectional view taken on line 2—2 of Figure 1 looking in the direction of the arrows.

Fig. 3 is a fragmentary sectional view of 25 the panel with a cord welt attached to its edges.

Fig. 4 is a detail view showing a cross-section of the inturned flanges provided on the inner face of the door.

30 Fig. 5 is a cross sectional view of a detail of a modified form of panel.

Fig. 6 is a similar view of a second modification.

Referring to the drawings, 1 designates a 35 metal automobile door and 2 the panel on the inner face thereof. The inner face of the metal door is provided with peripheral inturned flanges 3. The flanges at the upper and lower edges of said inner face extend 40 the full width of the door, and those at the side edges of said face are cut away at their lower ends, as shown in Fig. 1, for a purpose to be described hereinafter.

The panel 2, which may be made of any 45 suitable material but which is usually made of card board or fiber board covered with leather, real or artificial, and containing the usual flap-covered opening to the door pocket, is provided with a welt 4 secured to each 50 of its edges by stitching 5 or otherwise. This welt in Figs. 2 and 3 consists of a strip of suitable material folded about a cord, though as explained hereinafter, other ways of forming this welt are to be considered 55 within the scope of this invention.

With the construction above described, the method of assembling the panel with the door is as follows: The upper ends of the welts at the side edges of the panel are inserted beneath the side flanges at the lower ends of the latter, this operation being facilitated by reason of the side flanges being cut away at their lower ends, and then said panel is pushed upwardly, the corded portions of said welts at the side edges of said panel sliding beneath said side flanges until the corded portion of the welt at the upper edge of the panel contacts with the inturned flange A at the upper end of the door. The next step is to jam the welt at the upper edge 70 of the panel in under the flange at the upper end of the door. It will be noted, by reference to Figs. 2 and 4, that the flange 3 is curved inwardly on substantially the arc of a circle and that the distance between 75 the inturned edge of the flange and its base is considerably less than the thickness of the corded portion of the welt. It is comparatively easy, however, to jam the welt beneath the flange owing to the fact that said flange is made of relatively thin metal and, 80 hence, has considerable resilience and that the corded portion of the welt has sufficient give or resilience to permit it to be temporarily deformed. The final step is to spring 85 the portion of the welt at the lower edge of the panel beneath the flange at the lower end of the door. In carrying out this last operation it is necessary to slightly bend or buckle the lower end of the panel, which 90 is made possible by reason of the lower ends of the side flanges being cut away. The construction described above provides means whereby the panel may be quickly and securely assembled with and fastened to the 95 door without the use of nails, bolts, screws, or similar fastening means, and whereby, if for any reason it is desired to remove the panel, it is only necessary to reverse the order of the steps described for the assembly 100 of the panel with the door.

As an alternative of the above method of assembly, one of the flanges will not be curved inwardly until the panel is slid in place and the welts at three of its edges located beneath the three inturned flanges at the edges of the face of the door. The fourth flange will then be turned or rolled over upon the fourth edge of the panel to secure the panel in place. With this method 110

of assembly, it is not necessary to cut away any of the flanges as in the first method.

Still another method of assembly is not to slide opposite edge-portions of the panel beneath opposite flanges but simply to warp the panel slightly and then force its edge-portions beneath the flanges.

In the construction shown in Figs. 2 and 3, the panel is provided with corded welts at its edges. However, this construction is not absolutely essential, as the welts may be omitted entirely and the edge-portions of the panel itself located beneath the flanges. Where the welts are omitted, the panel may be provided as shown in Fig. 5 with a peripheral groove adjacent its edges to receive the inturned edges of the flanges, or the edge portions of the panel may be made slightly thicker than the body portion of the panel by making a two-fold straight or biased binding. This is made by doubling the leather, whether real or artificial, back on itself as shown in Fig. 6, at the edges of the board, before the edge of the leather or fabric that is being used is brought around under the board, to be finally secured by the stitching or otherwise. Since the welts secured to the edges of the panel no matter how formed, really constitute extensions of the edge-portions of the panel, wherever, in the claim, the expression edge-portions of the panel is used, it is to be construed as

covering either a construction in which the edge-portions of the panel are provided with extensions in the form of welts or in which such welts are omitted.

A construction as above described permits the panel and door to be made as separate units and to be readily assembled without the use of nails, screws, bolts, or similar fastening means. Also, when a panel becomes worn or damaged in any way, it may be readily removed for repairs or for the substitution of a new panel in place thereof.

Being aware that the particular embodiments of the invention shown and described are susceptible of considerable variation without departing from the spirit of the invention, therefore, I desire to claim the invention broadly as well as specifically as indicated by the appended claim.

What I claim as new and desire to secure by Letters Patent is:—

A vehicle door having on one face thereof resilient peripheral inwardly-curved flanges, and a panel covering said face and having edge portions located beneath and engaging said flanges, said panel having a peripheral groove or depression adjacent said edge-portions into which the edges of said flanges extend for detachably holding said panel to said door.

In testimony whereof, I affix my signature.
WALTER S. SMITH.
